UNITED STATES PATENT OFFICE.

HAMILTON DUDLEY COLEMAN, OF BILOXI, MISSISSIPPI.

PENCIL HOLDER.

Application filed July 14, 1924. Serial No. 725,942.

To all whom it may concern:

Be it known that I, HAMILTON DUDLEY COLEMAN, a citizen of the United States, residing at Biloxi, in the county of Harrison and State of Mississippi, have invented certain new and useful Improvements in Pencil Holders; and I do hereby declare the following to be a full, clear, and exact description of the invention, such as will enable others skilled in the art to which it appertains to make and use the same.

The object of the invention is to provide an improved pencil holder combined with a pencil and eraser in which the eraser operates with the holder to maintain the pencil frictionally in either end thereof.

With the foregoing and other objects in view, the invention will be more fully described hereinafter, and will be more particularly pointed out in the claims appended hereto.

In the drawings, wherein, like symbols refer to like or corresponding parts throughout the several views:—

25 Figure 1 is a side elevation of an improved holder constructed according to the present invention with the pencil in operative writing position.

30 Figure 2 is a similar view showing the pencil embraced within the other end of the holder when not in use.

Figure 3 is a longitudinal central section through the device in the writing condition.

Figure 4 is a perspective view of the 35 holder apart from the pencil.

Figure 5 is a section taken on the line 5—5 in Figure 1, and

Figure 6 is a similar cross section taken on the line 6—6 in Figure 2.

40 Referring more particularly to the drawings 7 designates the holder which is of tubular or cylindrical form and made from heavy paper, metal or other appropriate material preferably of a light weight. The 45 diameter of the tubular holder is only slightly greater than the pencil it receives, the pencil being of a short length such as is discarded at the present time and being pointed at both ends as indicated at 8 and 9 and having a rubber band 10 encircling the central or intermediate portion thereof.

50 The holder is split at both ends and at one end is provided with the slots 11 which are diametrically opposite one another and extend longitudinally of the holder. These 55 slots are narrow with substantially parallel

walls and extend into the holder a substantially lesser distance than the opposite and similar slots 12 in the other end of the holder. The slots in both ends of the holder 60 open out upon the ends and the slots 12 are also two in number and arranged diametrically opposite one another although turned an angular distance of 90 degrees from the slots 11 in the opposite end of the holder so that the 65 holder is not unduly weakened in a longitudinal direction. The slots 12 are preferably of slightly wedge shape and are considerably longer as compared with the slots 11 so as to entirely receive the double pointed 70 short length pencil within this end of the holder as shown in Figure 2.

In the use of the device the pencil normally occupies the position shown in Figure 2 in which the same is entirely encompassed 75 within the walls of the holder and in this position it is securely held by the frictional contact of the rubber band 10 upon the interior walls of the holder aided by the resilient clamping of the two sections of the 80 holder to opposite sides of the slots. The pencil in this condition may be carried about without the usual danger incident to the projecting points of well sharpened pencils and this end of the holder is adapted to receive the pencil in either position.

85 To utilize the implement for writing the pencil is removed from the slotted end 12 of the holder by inserting one of the fingers and the thumb along the slots and shifting 90 the same outwardly toward the end of the pencil, the finger and thumb catching in the rubber band affording a high adhesion, so that the pencil easily slips out of the holder.

95 The holder is thereupon reversed and the pencil inserted in the slotted end 11 where it can only be inserted for a short distance causing one of the points 8 or 9, which ever may be selected to protrude beyond the 100 holder as shown in Figure 1. The rubber band 10 fulfills the further function of an eraser.

105 It is obvious that various changes and modifications may be made in the details of construction and design of the above specifically described embodiment of this invention without departing from the spirit thereof, such changes and modifications being restricted only by the scope of the following claims:—

110 What is claimed is:—

1. A pencil holder comprising a tubular

holder having split ends with diametrically opposite slots extending axially of the holder and through the ends thereof, the slots at one end being offset circumferentially with respect to the slots at the other end of the holder and the slots at one end having divergent walls and being of greater length than the slots in the other end, and a short length of pencil sharpened upon both ends 10 having a rubber band extending about the intermediate part thereof and adapted to engage frictionally with the walls of the holder, said pencil adapted to be received wholly within the holder at the longer split 15 end thereof.

2. The combination of a pencil holder consisting of a tube made of resilient material and provided at each end with slots running parallel to the axis of the tube, the slots at one end being longer than those at the other, and a short pencil provided with a rubber band and sharpened at one or both ends and adapted to be wholly masked within the end of the holder provided with the longer slots, and to project from the end of 20 said holder, provided with the shorter slots, when mounted in said end, substantially as and for the purposes described. 25

HAMILTON DUDLEY COLEMAN.
